UNITED STATES PATENT OFFICE.

LAWRENCE J. ROSE, OF ST. LOUIS, MISSOURI.

DEVICE FOR FEEDING NONSLIP MATERIALS TO BRAKE LININGS.

Application filed October 29, 1924. Serial No. 746,512.

To all whom it may concern:

Be it known that I, LAWRENCE J. ROSE, a citizen of the United States of America, residing at the city of St. Louis, in the State of Missouri, have invented certain new and useful Improvements in Devices for Feeding Nonslip Materials to Brake Linings, of which the following is a specification, reference being had therein to the accompanying drawing.

10 My invention relates to improvements in devices for feeding non-slip material to brake linings, and has for its object to provide a chamber having an orifice extending 15 to the point of discharge of the non-slip material, and means controlled by the operator for releasing a charge of said material from the said chamber.

15 The class of material primarily intended 20 to be used with the device of my invention is the viscous compound now commonly used for the treatment or dressing of automobile brake linings; but the device is adapted to operate on non-slip material of various 25 types and to apply such material to brake linings of any type.

Drawings.

20 In the drawings, Fig. 1 is a side elevation 30 of the push mechanism actuating the device of my invention; the same being mounted in a section of floor, conveniently to the foot of the operator.

Fig. 2 is a longitudinal vertical view of 35 a device embodying my invention mounted in place upon a brake band.

Fig. 3 is a front view of the mechanism shown in Fig. 1, top and bottom being broken away.

40 Fig. 4 is a transverse vertical sectional view of the device shown in Fig. 2.

Fig. 5 is a plan view of the connections between the push mechanism and a pair of the devices, as mounted in an automobile.

45 Fig. 6 is a transverse sectional view taken on the line 6—6 of Fig. 2.

Description.

As shown in the drawings a cylindrical 50 container 7 having a conoidal bottom 8 and tubular discharge nozzle 9, mounted by brackets 10—10 upon the upper face of a brake band 11 having the brake lining 12; the nozzle 9 extending through the aperture 55 13 in the brakeband 11 and into the aperture 14 in the brake lining 12, as shown.

Within the cylindrical container 7 I provide the valve 15, which is in the form of a hollow tubular rod having the lower terminal nipple 16 extending into the interior of the nozzle 9, having the peripheral shoulder 17 whereon the perforated disk 18 is fixedly mounted and having a constricted upper terminal 19 extending through the center of the upper perforated disk 20, the coiled spring 40 being seated upon the upper face of the perforated disk 18 and holding the perforated disk 20 firmly in place against the lower mouth of the screw cap 22.

Through the hollow center of the tubular rod valve 15 extends the pin 21, as shown in Fig. 4, said pin 21 projecting to the mouth of the nozzle 9, its purpose being to prevent the clogging of said nozzle 9.

The perforated disk 20 is held in place 75 by the pressure of the screw cap 22 (see Figs. 2 and 4), which screw cap 22 has the concentric screw-threaded mouth 23, which mouth 23 is in turn provided with the closure 24. The goose-neck lever 25 is 80 mounted transversely through the container 7 as shown in Fig. 4, its hump 26 being so disposed as to operate against the bottom of the perforated disk 18, before opening the valve 15, while its terminal crank arm 27, having the eye 28 at its free extremity, is connected with the corresponding eye 29 by the cord 30, and is actuated by pressure exerted upon the button 31, depressing the push rod 32 having the foot 33 bearing upon 90 the arm 34 of the lever 35, which is fulcrumed on the pin 36, all as shown in Fig. 1. The device thus described is usually to be mounted in pairs as shown in Fig. 5, so a single one of the push button mechanisms shown in Fig. 1 will serve to operate the pair of devices.

It is desirable with a non-slip material of the kinds now commonly used for the treatment of brake linings, to be able to ascertain when the container 7 is fully charged 100 with such material; and for that purpose I provide near the edge of the mouth of the container 7 the vent 37, and within the screw cap 22 the vent 38, these vents being so disposed that they will register with each other when the screw cap 22 is almost, but not quite, closed. While the material is being charged in the container 7 through the tubular mouth 23 of the screw cap 22 vents 110 37 and 38 are to be kept in alignment, so that when the charge of material has risen

to the level of said vents 37 and 38 it will discharge through said vents, whereupon a short turn of the screw cap 22 will carry said vents out of alinement to the relative 5 positions shown in Fig. 6, and the closure 24 will thereupon be seated in place, the device being properly charged for use.

Mode of operation.

10 As will be apparent from the foregoing description of the various parts of my device the discharging of non-slip material from the container 7 is under the control of the driver of the motor vehicle on which 15 my device is installed; the failure of the brakes to grip properly being indicated by their failure to promptly hold when applied, a depression of the push button 31 working through the cord 30 serves to throw the 20 crank 26 against the lower face of the perforated disk 18, opening the valve 15 and permitting a charge of non-slip material to drop into the nozzle 9 and so into the orifice 14 in the brake lining. This operation is 25 usually performed while the vehicle is in motion; the non-slip material passes through the orifice 14 to the face of the drum 40, the rotation of which drum 40 serves to distribute the non-slip material 30 upon the face of the brake-lining 12. This operation is repeated as often as the necessity for treating the brake lining is indicated.

Various modifications may be made from

the device as illustrated and described without departing from my actual invention, as that invention is defined in the following claims.

Claims:

1. In a device of the class described, a container mounted upon a brake band; a terminal nozzle therefor extending through the brake band to the brake lining; a valve control for said nozzle; a screw cap for said container and vents formed respectively on said container and said screw cap and arranged to be thrown into or out of registration with each other. 40

2. A device of the class described comprising a pair of valve-controlled containers, each mounted upon a brake band and each having a nozzle extending through the brake band whereon it is mounted to the brake lining; and a single push-button mechanism arranged to simultaneously operate both of said containers. 50

3. In a device of the class described, a container mounted upon a brake band; a nozzle therefor extending through the brake band to the brake lining; a tubular rod valve having a lower terminal nipple extending into the interior of the said nozzle; and a pin mounted in said tubular rod valve and projecting to the mouth of said nozzle. 60

In testimony whereof I have hereunto affixed my signature.

LAWRENCE J. ROSE.
